United States Patent Office

Des. 210,869
Patented Apr. 30, 1968

210,869

PLASTIC BOX

Thomas H. Hayes, Roanoke, Va., assignor to Creative Packaging Incorporated

Filed Nov. 30, 1966, Ser. No. 4,863

Term of patent 14 years

(Cl. D9—235)

Fig. 1

Fig. 5

Fig. 2

Fig. 4

Fig. 3

FIG. 1 is a top perspective view of a plastic box showing my new design;

FIG. 2 is a bottom plan view thereof;

FIG. 3 is a front elevation thereof;

FIG. 4 is an end elevation thereof; and

FIG. 5 is a rear elevation thereof.

I claim:

The ornamental design for a plastic box, as shown.
